(57) CLAIM

The ornamental design for a case for interchangeable lens, as shown and described.

DESCRIPTION

FIG. 1 is a front view of a case for interchangeable lens showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The broken line showing portions of the disclosure are for illustrative purposes only and form no part of the claimed design.
